CLAIM

The ornamental design for a tail light, as shown and described.

DESCRIPTION

FIG. 1 is a right side rear perspective view of a tail light showing the new design as positioned within a vehicle; FIG. 2 is a left side rear perspective view of the tail light illustrated in FIG. 1;

FIG. 3 is a center rear view of the tail light illustrated in FIG. 1;

FIG. 4 is a left side view of the tail light illustrated in FIG. 1;

FIG. 5 is a right side view of the tail light illustrated in FIG. 1;

FIG. 6 is a top elevation view of the tail light illustrated in FIG. 1;

FIG. 7 is an enlarged partial view of the tail light illustrated in FIG. 1;

FIG. 8 is an enlarged partial view of the tail light as illustrated in FIG. 7, but with the outer clear cover cut away at the symbolic wavy break line so that the underlying visible surfaces are illustrated; and,

FIG. 9 is a cross sectional view of the tail light as illustrated in FIG. 2.

The broken lines are included for the purpose of illustrating environmental subject matter and form no part of the claimed design. The cross sectional surface and the non-visible rear facing surfaces illustrated in the cut away view are not part of the claimed design as indicated by the broken cross hatched lines in FIG. 9.

1 Claim, 9 Drawing Sheets
